(57) **CLAIM**

The ornamental design for a faucet as shown and described.

DESCRIPTION

FIG. 1.1 is a front perspective view showing the new design; FIG. 1.2 is a top plan view thereof; FIG. 1.3 is a bottom plan view thereof; FIG. 1.4 is a front view thereof; FIG. 1.5 is a back view thereof; FIG. 1.6 is a left side view thereof; and FIG. 1.7 is a right side view thereof.

The design is characterized by features represented in solid lines; protection is not claimed for parts in broken, dotted or dash-dot lines; the broken lines shown in the drawings represent unclaimed portions of the faucet and form no part of the claimed design; the appearance of any portion of the article between the broken away symbols forms no part of the claimed design; the purpose of the dash dotted lines in figures from 1.1 to 1.7 is to delimit portions of variable length of the products, the borders of which are represented in dotted lines.
